UNITED STATES PATENT OFFICE.

CHARLES WHITTINGHAM, OF CLEVELAND, OHIO.

DESIGN FOR A GAS COOK-STOVE.

SPECIFICATION forming part of Design No. 23,529, dated July 31, 1894.

Application filed July 3, 1894. Serial No. 516,505. Term of patent 7 years.

To all whom it may concern:

Be it known that I, CHARLES WHITTINGHAM, a citizen of the United States, residing at Cleveland, in the county of Cuyahoga and 5 State of Ohio, have invented and produced a new and original Design for Gas Cook-Stoves, of which the following is a specification, reference being had to the accompanying drawings, showing a part thereof.

Figure 1 is a plan view of a gas stove, showing my new design, and Fig. 2 is a side elevation thereof.

The design is revealed in both the plan and side views together, because both enter into 15 the make up by which the burner is distinguished.

The surface A of the base is finished to form a decorative border extending entirely around the stove and nearly its entire depth, and said 20 border is produced by alternating straight vertical grooves or channels —4— at regular and frequent intervals, and flat faced ribs or panels —5— between the said grooves and of about the same width. The grooves —4— 25 begin somewhat above the lower edge of the border and terminate under the slightly overlapping plain surfaced rim —6— immediately above. The handles C of the valves are fashioned in imitation substantially of a rosette, 30 and add to the general appearance of the front of the stove.

Between the border A and the tops of the

grate bars D we see, first, the plain surfaced overlapping rim —6—, and then above this rim is another distinct and separate figured border E, extending around each burner. This border E is set at such inward inclination and curvature as to distinctly reveal itself to the eye in both plan and side views, and hence is always present to the eye as a 40 decorative feature of the stove. Between each set of borders E is the transverse figured panel —8— standing out in clear relief from the said borders and flush with the top of the grate bars D. 45

The grate bars D start from the border E and converge toward the center of the burner. These bars are divided off into four quarters in each burner by the four long central bars —a—. Then there are three shorter bars —b— 50 between the bars —a— and four shorter bars still alternately between the bars —b—. These bars thus arranged with the ring F constitute a distinguishing and attractive feature of these burners. 55

Having thus described my invention, what I claim as new, and desire to secure by Letters Patent, is—

The design for a gas stove substantially as herein shown and described.

CHARLES WHITTINGHAM.
